UNITED STATES PATENT OFFICE

WALDO HAYS Wiest, OF CHICAGO, ILLINOIS

DESIGN FOR A STATUE

Application filed July 1, 1929. Serial No. 31,919. Term of patent 14 years.

To all whom it may concern:

Be it known that I, WALDO HAYS Wiest, a citizen of the United States, residing at Chicago, in the county of Cook and State of Illinois, have invented a new, original, and ornamental Design for Statues, of which the following is a specification reference being had to the accompanying drawings, forming a part thereof, in which—

Fig. 2 is an elevation of one side of the statue;

Fig. 3 is an elevation of the opposite side of the statue with the base omitted, and

Fig. 4 is a rear elevation of the statue.

I claim:

The ornamental design for a statue substantially as shown.

In witness whereof, I have hereunto subscribed my name.

WALDO HAYS Wiest.
